CLAIM

The ornamental design for a light unit for a vehicle, as shown and described in FIGS. 1-9, with the mounting brackets, contour, shading lines and electrical couplings forming no part of the design.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a light unit for a vehicle in accordance with one embodiment;

FIG. 2 is a front view of the light unit for a vehicle as shown in FIG. 1;

FIG. 3 is a rear perspective view of the light unit for a vehicle as shown in FIG. 1;

FIG. 4 is a right side view of the light unit for a vehicle as shown in FIG. 1;

FIG. 5 is a left side view of the light unit for a vehicle as shown in FIG. 1;

FIG. 6 is a plan view of the light unit for a vehicle as shown in FIG. 1;

FIG. 7 is a lower view of the light unit for a vehicle as shown in FIG. 1;

FIG. 8 is a rear view of the light unit for a vehicle as shown in FIG. 1; and,

FIG. 9 is a three-dimensional mockup of the light unit for a vehicle as shown in FIG. 1.
